US0D1086036S

(12) **United States Design Patent** (10) **Patent No.:** **US D1,086,036 S**
(45) **Date of Patent:** **** Jul. 29, 2025**

(54) **CHARGING STATION**

(71) Applicant: **Volta Charging, LLC**, San Francisco, CA (US)

(72) Inventors: **Scott A. Mercer**, Pacifica, CA (US); **Alex Prodaniuk**, Pacifica, CA (US); **Stephan Lintner**, Anif-Salzburg (AT); **Julian Schloemer**, Salzburg (AT); **Marco Wilhelm**, Salzburg (AT)

(73) Assignee: **Volta Charging, LLC**

(**) Term: **15 Years**

(21) Appl. No.: **29/975,858**

(22) Filed: **Dec. 2, 2024**

Related U.S. Application Data

(63) Continuation of application No. 29/832,261, filed on Mar. 25, 2022, now Pat. No. Des. 1,059,272, which is a continuation of application No. 29/757,238, filed on Nov. 4, 2020, now Pat. No. Des. 950,485.

(51) **LOC (15) Cl.** **13-02**

(57) **CLAIM**

The ornamental design for a charging station as shown and described.

DESCRIPTION

FIG. 1 is a front perspective view of a charging station showing our new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The dash-dot-dash broken lines illustrate boundaries that form no part of the claimed design. The dash-dot broken lines depict features of the charging station that form no part of the claimed design.

1 Claim, 4 Drawing Sheets
